Primary Examiner — Michael C Stout*Assistant Examiner* — Fitzgerald L Butac(74) *Attorney, Agent, or Firm* — Marshall, Gerstein & Borun LLP(57) **CLAIM**

The ornamental design for a body panel for a machine, as shown and described.

DESCRIPTION

FIG. 1 is a top, front, and right-side perspective view of a body panel for a machine, showing our new design.

FIG. 2 is a top plan view.

FIG. 3 is a right-side elevation view.

FIG. 4 is a front elevation view.

FIG. 5 is a back elevation view.

FIG. 6 is a left-side elevation view; and,

FIG. 7 is a bottom plan view.

The broken lines show portions of a body panel for a machine which form no part of the claimed design.
